UNITED STATES PATENT OFFICE.

GEORGE NICHOLS, OF NEW YORK, N. Y.

DESIGN FOR A BRACKET FOR SUPPORTING TROLLEY-WIRES.

No. 38,462.

Specification for Design.

Patented Feb. 19, 1907.

Application filed January 12, 1907. Serial No. 352,065. Term of patent 14 years.

To all whom it may concern:

Be it known that I, GEORGE NICHOLS, a citizen of the United States, residing at New York, county of Kings, State of New York, have invented a new, original, and ornamental Design for Brackets for Supporting Trolley-Wires, of which the following is a specification, reference being had to the accompanying drawing, forming part thereof.

The figure is a side view of a bracket for

supporting a trolley-wire, showing my new design.

I claim—

The ornamental design for a bracket for supporting a trolley-wire as shown.

GEORGE NICHOLS.
